UNITED STATES PATENT OFFICE.

WRIGHT R. PHARES, OF CENTERVILLE, IOWA.

STOVEPIPE-FASTENER.

No. 923,441.

Specification of Letters Patent.

Patented June 1, 1909.

Application filed January 2, 1908. Serial No. 408,989.

To all whom it may concern:

Be it known that I, WRIGHT R. PHARES, a citizen of the United States, residing at Centerville, in the county of Appanoose and State of Iowa, have invented certain new and useful Improvements in Stovepipe-Fasteners, of which the following is a specification, reference being had therein to the accompanying drawing.

10 This invention relates to improvements in stovepipe fasteners, and has for its object the provision of means for facilitating the securing of a stovepipe in a sleeve or thimble or an aperture communicating with the flue of the 15 chimney, or like escape-duct.

Another object of the invention is the construction of a stove-pipe fastener, which comprises a minimum number of parts, is efficient in operation, and owing to its simplicity of structure, is comparatively inexpensive to manufacture.

With these and other objects in view, the invention consists of certain other novel constructions, combinations, and arrangements 25 of parts, as will be hereinafter fully described and claimed.

In the drawings: Figure 1 is a longitudinal, sectional view of a stovepipe and a thimble carried by a portion of a chimney and showing, in section, my fastener holding said pipe in the thimble or sleeve. Fig. 2 is a view in front elevation of the device constructed in accordance with the present invention, showing in section, a pipe therein. Fig. 3 is a perspective view of my stovepipe fastener.

Referring to the drawings by numerals, 1 designates a chimney, preferably, carrying a thimble or sleeve 2 in the stovepipe aperture or opening thereof. The hereinafter described fastener is just as susceptible of holding the stovepipe 3 in the stovepipe opening or aperture, even though no thimble or sleeve 2 is mounted therein, although the dimensions of the part will have to be varied, or 40 will be such as to produce the same effect as when the thimble or sleeve is in the hole or opening of the chimney.

My stovepipe fastener comprises an annular collar or cap-plate 4, which is concavo- 50 convexed in transverse section. A plurality of spring-arms or holder-members 5 are attached to the inner face of the sleeve or cap-plate 4, by any suitable fastening means, as for instance, rivets 5. Each spring-arm or 55 holder-member is, preferably, formed from springy or resilient sheet-metal or strip, and

comprises outwardly or upwardly bowed or curved body portion 6, which terminates at its inner end, in a flat, straight pipe-engaging portion 7, and the inner straight pipe-engaging portion 7 terminates at its inner end in a laterally-extending or right-angle collar-engaging portion 8, through which, fastening means or rivet 5 extends. The outer end of the body portion 5 is integral 60 with a horizontal U-shaped portion 9, which is provided with flat, parallel sides 10, that fit snug against the inner and outer walls of the pipe 3 and clamp said pipe for normally resisting outward strain or pull that may be 65 exerted upon the pipe 3. The U-shaped, inner end of the arms or members also prevent the stovepipe 8 from being shoved too far into the chimney, as they limit the inward movement of the pipe within the pipe- 75 opening or within the thimble or sleeve 2.

Prior to the insertion of the stovepipe 3 into the pipe-opening or sleeve, if the sleeve is mounted in the opening, I place upon the pipe the fastening-device, causing the ordinary inwardly-extending corrugated end 11 of the pipe to be inserted into the U-shaped portions of the arms or holder-members, and then the outer side 10 of the U-shaped portion 9 and the flat portions 7 of each finger 85 will be in engagement with the outer wall or surface of the pipe; it is to be noted that the portions 9 extend slightly inward to conform to the inwardly-extending structure of the corrugated end 9 of the pipe. Upon forcing 90 the pipe 3 into the pipe-aperture or the sleeve 2, the outwardly or upwardly-bulged or curved body 6 will engage the inner face of the sleeve 2 or the pipe-opening, as the case may be, causing the flat portions at the ends 95 of each curved or bulged body 6, to bear downward and grip the pipe, while at the same time, said body is also gripping the sleeve 2, thereby exerting a frictional resistance against the pipe 3 being removed by accident or any sudden jar, which is very important, owing to the liability of great damage being done by the stovepipe accidentally being detached from the chimney.

It is to be noted that I have provided upon 105 each spring-arm or holder-member, flat, pipe-engaging portions near its ends, connected by a chimney or flue-engaging body or clamping-portion; the outer pipe-engaging portion constituting a part of a clamping- 110 device or U-shaped member which engages opposite portions of the pipe for gripping

said pipe and limiting its inward movement upon the flue or chimney 1.

From actual experience, I have found that my peculiar structure of the arm produces a very efficient device which obviates any possibility of the pipe becoming displaced off of the chimney or flue, under normal conditions, and at the same time, producing a device by means of which the operator can 10 easily secure the stovepipe to the chimney and remove the same quickly, if desired.

It is to be noted that the inner collar-engaging portion 8 of each arm or holder-member lies parallel with the inner face of the 15 collar, and is, consequently, curved or bowed.

It is to be noted that by reason of the fact that the pipe 3 is provided with a corrugated end 10, the portions 9 are bent or extend slightly inwardly to fit snug over this end for 20 the purpose of producing a hook-structure for facilitating the fastening of the strips 5 to the pipe so that the fastening device cannot be easily displaced or accidentally removed; the slight inward-bending of the portions 9 25 and the inwardly-extending structure of the corrugated end, place the extreme edge of the end 11 and portions 9 below the inner walls of the pipe, thereby forming a hook-structure. Furthermore, by reason of the 30 outwardly-bowed or arched portion 6, the locking device engages the flue even though the pipe is nearly withdrawn from the flue, which would not be the case if the bowed or arched portion extended inwardly, thereby 35 producing a very efficient fastening device

which prevents accidental displacement of the pipe until the pipe is entirely removed, or practically so from the flue or thimble 2.

What I claim is:

In a device of the character described, the 40 combination of a stovepipe, provided with an inwardly-extending corrugated-end, a collar mounted upon said pipe, of a fastener for said pipe, comprising flat strips of spring-metal having their central portion outwardly- 45 bowed or arched, and provided with inner and outer flat horizontal-arms on the opposite terminals of the bows, said arms of each strip formed in the same vertical plane with the arched portion, and serving to contact 50 with the outer surface of the stovepipe throughout their lengths, the ends of the inner arms being bent at right-angles therewith and positioned vertically and secured snug against the collar, and the outer ends of 55 the outer arms being bent upon themselves to form inwardly-extending hooks which are inserted over the corrugated-end of the stovepipe so as to contact the entire length with the inner and outer surfaces thereof and 60 form a hooked-structure, whereby accidental displacement of the arms off of the pipe is prevented, substantially as specified.

In testimony whereof I hereunto affix my signature in presence of two witnesses.

WRIGHT R. PHARES.
